UNITED STATES PATENT OFFICE.

CHARLES STEIN AND WILLIAM M. HELLER, OF ATLANTIC CITY, NEW JERSEY.

DESIGN FOR A DOLL.

Application filed May 25, 1927. Serial No. 22,164. Term of patent 14 years.

To all whom it may concern:

Be it known that we, CHARLES STEIN and WILLIAM M. HELLER, both citizens of the United States, and residents of Atlantic City, county of Atlantic, State of New Jersey, have invented a new, original, and ornamental Design for Dolls, of which the following is a specification, reference being had to the accompanying drawings, forming a part thereof.

Fig. 1 is a perspective view from the front of the doll showing our design; and Fig. 2 is an edge view thereof.

We claim:

The ornamental design for a doll as shown.

In testimony whereof we hereunto affix our names.

CHARLES STEIN.
WILLIAM H. HELLER.
